(57) **CLAIM**

The ornamental design for a base unit of a food blender as shown and described.

DESCRIPTION

FIG. 1 is a front-right side perspective view showing the new design for a base unit of a food blender;

FIG. 2 is a front view illustrating the base unit of the food blender;

FIG. 3 is a rear side view illustrating the base unit of the food blender;

FIG. 4 is a left-side view illustrating the base unit of the food blender;

FIG. 5 is a right-side view illustrating the base unit of the food blender;

FIG. 6 is a top plan view illustrating the base unit of the food blender; and,

FIG. 7 is a bottom view illustrating the base unit of the food blender.

The novelty in the design resides in the features of the shape of the article as shown in the representations. The broken lines showing portions of the base unit of a food blender form no part of the claimed design.

1 Claim, 7 Drawing Sheets
